UNITED STATES PATENT OFFICE.

OSCAR KNOCH, OF ESSEN-ON-THE-RUHR, GERMANY, ASSIGNOR TO FRIED. KRUPP AKTIENGESELLSCHAFT, OF ESSEN-ON-THE-RUHR, GERMANY.

PRESSURE-RELIEVING TRUNNION-BEARING FOR GUNS.

1,190,299.

Specification of Letters Patent.

Patented July 11, 1916.

Application filed September 11, 1913. Serial No. 789,320.

To all whom it may concern:

Be it known that I, OSCAR KNOCH, residing at Essen-on-the-Ruhr, Germany, a subject of the Emperor of Germany, have invented a certain new and useful Improvement 5 in Pressure-Relieving Trunnion-Bearings for Guns, of which the following is a specification.

The present invention relates to pressure 10 relieving bearings for guns and consists in improvements in trunnion bearings of this kind for preventing lateral displacement, during firing of the gun, out of its firing direction.

One embodiment of the invention is illustrated 15 in the accompanying drawing and Figure 1 shows an elevation of the left hand trunnion bearing and Fig. 2 a cross section of Fig. 1 along line 2—2 of the left hand bearing, and along 2x—2x of the right hand trunnion bearing, the cradle and the gun being represented in rear elevation.

The gun A is slidably mounted in the cradle B, which latter is mounted by means 25 of the main trunnions C in the body of the carriage D. The bodies D¹ of the bearings are open on the side toward the breech of the gun, and closed by caps d², the perpendicular inner wall d⁴ of the cap d², and the 30 opposite wall d³ of the bearing body D¹ constituting guiding surfaces for a sleeve E, in which the main trunnion C is mounted without play. The sliding surfaces d³ d⁴ abut without play against the sliding surface e¹ and e² of the sleeve E, while the 35 sleeve E may be slightly displaced in a vertical direction in the bearing D¹—d².

Each of the main trunnions C is provided 40 with a smaller trunnion c¹; situated outside the sleeve E, and the axis of which coincides with the axis of the main trunnion. The auxiliary trunnions c¹ each rest on a sled G and are supported by rollers H traveling on a rail J. The rail J may be adjusted in a 45 vertical direction by means of two set screws K threaded in a projection d⁵ on the bearing body D¹.

The screwing in of the screws K causes

a raising of the auxiliary trunnions c¹ and as a consequence also of the cradle and of 50 the gun barrel. The trunnion sleeves E will then be lifted from their bottom bearings to relieve them from the weight of the gun barrel and the cradle. As the main trunnions C are mounted without play in the 55 sleeves E and the sleeves in their turn are guided without play in the bearing body D' between the guiding surfaces d³ and d⁴ which run in the direction of the bearing-relieving movement, the gun barrel during 60 firing will be effectually prevented from turning sidewise out of firing direction. The gun retains therefore, during firing, its position relative to the sight line so that an error in the side direction will be prevented. 65

I claim:

1. Pressure relieving trunnion bearings for guns provided with trunnions comprising a sleeve without play on each trunnion, a bearing body for said sleeve, said sleeve 70 being guided without play in the bearing body between guiding surfaces which run in the direction of the bearing-relieving movement and an auxiliary trunnion on each of the main trunnions and in alinement 75 therewith, said auxiliary trunnion having a vertically adjustable seat on the bearing body.

2. Pressure relieving trunnion bearings for guns provided with trunnions, comprising a sleeve without play on each trunnion, said sleeve having straight outside surfaces, a bearing body open on one side and a cap for closing said opening, said bearing body and cap fitting closely in all directions 80 around the sleeve only permitting vertical displacement of the sleeve; an auxiliary trunnion on each of the main trunnions and in alinement therewith, a sled mounted on a pair of rollers supporting each auxiliary 90 trunnion, a rail for carrying the rollers, set screws under the rail, said screws being vertically adjustable in a ledge on the bearing body; whereby said sleeves will be relieved 95 from the weight of the gun on raising said sleds, rollers and rails by means of said

screws, and transverse turning of the gun men, Germany, this 21st day of August, out of its given firing direction will be prevented, said rollers being provided with 1913.
5 guide flanges engaging both with said rail and said sled, whereby the sled is guided by the rollers and the rollers by the rail.

The foregoing specification signed at Bar-

OSCAR KNOCH. [L.S.]

In presence of—
ALBERT NUFER,
JULIUS FESTNER.
